UMBRELLA SHEATH

Richard Zimmermann, Leichlingen, Rhineland, Germany,
assignor to Bauermann & Soehne G.m.b.H., Hilden,
Rhineland, Germany

Filed Nov. 24, 1969, Ser. No. 20,249

Claims priority, application Germany June 7, 1969

Term of patent 14 years

Int. Cl. D3—99

U.S. Cl. D87—1

The figure is a perspective view of an umbrella sheath showing my new design; the portions not seen are plain and unornamented.

I claim:

The ornamental design for an umbrella sheath, substantially as shown and described.
